UNITED STATES PATENT OFFICE.

FREDERICK E. BLODGETT, OF NEWARK, NEW JERSEY, ASSIGNOR TO YOUNG MANUFACTURING COMPANY, OF NEWARK, NEW JERSEY, A CORPORATION OF NEW JERSEY.

SAFETY-RAZOR.

1,017,199.

Specification of Letters Patent. Patented Feb. 13, 1912.

Application filed January 20, 1911. Serial No. 603,636.

To all whom it may concern:

Be it known that I, FREDERICK E. BLODGETT, a citizen of the United States, residing at Newark, in the county of Essex and State 5 of New Jersey, have invented certain new and useful Improvements in Safety-Razors, of which the following is a specification, reference being had therein to the accompanying drawing.

- 10 My invention relates to safety razors of the type in which a removable blade is detachably clamped when in use, the objects of the invention among others being to provide for clamping the blade securely and 15 fixedly to its seat in a predetermined relation to the guard; to enable a flat single-edged blade to be held and employed in a superior manner; to provide for the simple application and removal of the blade; to 20 enable the blade to be clamped without bending and in such manner as to maintain it entirely free from the guard or comb; and generally to improve and simplify the construction of the device as a whole.
- 25 With these ends in view my invention consists of various improved features of construction in the form and arrangement of parts which will be fully pointed out in the specification.
- 30 I will first describe a form of razor embodying my improvements and will then set forth the novel features thereof in the claim.

Figure 1 is a perspective view showing the blade and all of the clamping parts in substantially the relation that they will have when in use, save that for the purposes of illustration they have been slightly separated. Fig. 2 is a face view of the top plate engaged by a blade. Fig. 3 is a central 40 transverse section of the assembled razor.

Similar letters of reference are employed to designate corresponding parts in the several figures.

A represents a form of blade suitable for 45 use in the present improvements, this being shown as of a flat form and as having only one of the long edges sharpened, the other long edge constituting the back edge *a* of the blade.

50 *a'* is an aperture arranged substantially central in the blade for a purpose that will hereinafter appear.

On either side of the blade and clamping the same flatwise between them, are two 55 plates B and C. The uppermost of these

plates in the drawings may be termed the holder plate B and the lower plate may be termed the guard plate C, both of them being substantially flat with the exceptions of the lugs and guard to be hereinafter referred to.

As a means of holding all of the parts together into a rigid whole, a clamping means is employed in the form of a clamping screw which also constitutes a center lug *b* located 65 substantially central of the holder plate and projecting toward the guard plate. It has been stated that the blade is apertured and this aperture is so located as to coöperate with the center lug *b* of the holder plate, 70 said lug also passing through an aperture *c* in the guard plate C, the screw thread at the outer end of the center lug allowing a nut or other device such as the threaded interior of a handle end to be applied 75 thereto.

D represents a handle having its end *d* threaded interiorly to coöperate with the clamping screw so that the handle may be applied and turned tightly into such position as to clamp all of the four described parts tightly together.

In order to properly justify the blade and hold it in its position, I employ means located on one of the two plates B and C, preferably on the holder plate B, of such nature as to engage with the blade at three points not in a straight line but constituting the three corners of a triangle. One of these points of engagement is that already referred to, afforded by the center lug coöperating with the center hole in the blade. The other two points which are most clearly seen in Fig. 2, are a pair of lugs at the side or near the corner farthest from the cutting edge of the blade, said lugs being formed on one of the two plates, preferably the holder plate B, and the lugs being indicated on the drawings by the letters *b'*, *b''*. From Fig. 90 2 it will be seen that the blade when adjusted on the center lug slips down into place with its rear or unsharpened edge in abutment against the lugs *b'*, *b''*, thus affording three points of contact or adjustment which accurately determine the position of the blade and thereby insure its cutting edge having proper relation to the guard hereinafter to be referred to.

On the guard plate C is a guard *e'* in the form of a comb which is somewhat curved 110

away from the sharp edge of the blade A so as to leave the blade edge free from any contact with or pressure by the guard, this being a decided advantage in that the cutting capacity of the blade is not in any way interfered with by the guard and the guard takes no part in the clamping of the blade in place.

From the above description it will be seen
 10 that a very simple and efficient safety razor is afforded, it consisting merely of three parts in addition to the blade, and so related as to not only very accurately justify the blade, but also to tightly clamp it flatwise
 15 beyond the possibility of displacement in its proper position and in exact predetermined relation to the guard or comb; the most approved relation of the blade and the plates between which it is clamped to the
 20 handle, is afforded; and the entire structure is inexpensive and at the same time durable.

The threaded handle D may be considered as a locking device or locking handle since when the other three members are in position
 25 it may be screwed upon the lug for locking the parts in proper relative positions with the blade accurately clamped in exact relation to the guard.

While in the accompanying drawings I

have shown my invention embodied in the 30 form which I prefer to adopt and which in practice has been found to answer the ends to be attained, it will be understood that the invention is not to be limited to such details as are shown, nor to any particular form or 35 relation of the parts except in so far as such limitations to form or relation are specified in the appended claim.

What I claim and desire to secure by Letters Patent is:

In a safety razor, the combination of a flat, single-edged, apertured blade, a flat holder plate, a flat guard plate, means for positioning said blade with respect to said plates, a threaded locking handle for locking 40 the three, and a guard or comb on said guard plate; said positioning means comprising a pair of lugs engaging the blade back-edge and a threaded lug engaging the blade aperture, said threaded lug adapted to be engaged by said locking handle.

In testimony whereof I affix my signature in presence of two witnesses.

FREDERICK E. BLODGETT.
